UNITED STATES PATENT OFFICE

97,003

DESIGN FOR AN ELECTRIC HEATER CASING

George Steingruber, Huntsville, Ala.

Application June 24, 1935, Serial No. 57,390

Term of patent 7 years

To all whom it may concern:

Be it known that I, George Steingruber, a citizen of the United States, residing at Huntsville, in the county of Madison and State of Alabama, have invented a new, original, and ornamental Design for Electric Heater Casings, of which the following is a specification, reference being had to the accompanying drawing, forming part thereof.

The figure of the drawing is a perspective view of the casing showing my new design. The hidden side is similar to the side illustrated in the drawing.

I claim:

The ornamental design for an electric heater casing, substantially as shown and described.

GEORGE STEINGRUBER.
